UNITED STATES PATENT OFFICE.

ANTON ZEMAN, OF CHICAGO, ILLINOIS, ASSIGNOR TO JOSEPH SALTZMAN, OF CHICAGO, ILLINOIS.

PRESSING MACHINE.

Original application filed January 16, 1924, Serial No. 686,479. Divided and this application filed July 13, 1926. Serial No. 122,098.

My invention has reference more particularly to pressing machines of the type used in tailor shops and other similar establishments, for pressing clothes.

5 The principal objects of my invention are to provide an improved pressing machine; to provide means for automatically governing or regulating the temperature of the pressing element; and in general, to simplify and increase the efficiency of pressing machines of this type. This application is a divisional of application Serial No. 686,479, filed January 16, 1924 which has become Patent No. 1,620,248, dated March 8, 1927.

15 On the drawings:

Fig. 1 is a side view of a pressing machine embodying my improvements, with parts broken away to disclose details of the construction.

20 Fig. 2 is a detail sectional view on the line 2—2 of Fig. 1.

Referring to the drawings, the reference numeral 1 indicates the base of the machine which is preferably formed integral with 25 the pair of side standards which are suitably connected at the top and otherwise as shown in my prior patent above referred to. A shaft or upright standard 5 is mounted in a substantially upright position at the rear 30 of the frame between the side standards and projects upwardly through a notch in the rear of the top.

The carriage of the machine is indicated at 40 and consists of an elongated head with 35 an opening extending therethrough from end to end to loosely receive the bar 41 which is engaged between the upper and lower anti-friction rollers 42, which are journaled in the head and permit easy sliding movement of the bar 41 through the head. This head is formed with a pair of vertically spaced collar portions 43 and 44 which embrace the upper end of the shaft 5 and have a collar or sleeve 45 interposed 45 therebetween and secured on the shaft 5 by the pin 46 or in any other convenient manner.

In cases where this machine is provided with an ordinary iron which it is desired to move along the upper surface of the pressing buck, the collars 43 and 44 are free to turn on the shaft 5. In the present structure, however, a pressing element 47 is employed, which merely clamps down against the top of the buck 48 and as sidewise lat-

eral movement or oscillation is not desired, 55 the collars 43 and 44 are locked onto the shaft 5 by the pins 49 or in any other convenient manner.

Seen end to the forward end of the bar 41 is a cross head 50 which supports the pressing element 47. The latter comprises an elongated shell having a flat bottom corresponding in form to the top surface of the pressing table or buck 48 and adjustably connected at spaced points by means of 60 the screws 51 to the ends of the cross head 50. These screws 51 have hand wheels 50' for turning them, and notched portions 51' engaged by catches 52' to keep the screws from accidentally turning when adjusted to 65 give the required uniform pressure on the garments. A handle 52 is attached to the front of the pressing element 47 for convenient manipulation of the latter.

Extending lengthwise within the heating 75 element 47 is a gas burner 53, which has an inlet pipe 54 connected thereto at the center, and this inlet pipe is connected through the manually operable valve 55 by the hose 56 to a gas supply pipe 57, the hose being sufficiently loose and suitably caught up as indicated at 58 so that the pressing element may be readily raised and lowered and moved backwardly and forwardly on the 80 pressing machine.

A similar gas burner 62 is mounted under the top plate of the pressing table 48 and has the inlet pipe 63 at the center connected through the manually operable valve 64 and tubing 65 to the main supply pipe 57. A 90 valve 66 which is automatically operable by a thermostat, is connected to the supply pipe 57 so as to simultaneously control the admission of gas to both of the heating elements 53 and 62, the device of this automatic valve 95 not being shown, as such valves are already on the market, and any suitable thermostatically operated valve may be employed. A thermostatic element 67 is mounted by means of brackets 68 under the top plate of 100 the pressing table 48 and connected by means of the tubing 69 with the automatic valve 66 in the usual manner for controlling the operation thereof. A handle 70 on this valve serves to set the latter at any desired temperature which is automatically maintained by the valve through the medium of the 105 thermostatic element 67.

With this construction, when the handle 70 is set at the temperature desired for pressing, the flow of gas through the tubes 56 and 65 to the burners 53 and 62 is automatically regulated so as to maintain the required temperature. A manually operable valve 71 is provided in the supply pipe 57 for entirely shutting off the supply of gas.

While I have shown and described my invention in a preferred form, I am aware that various changes and modifications may be made without departing from the principles of my invention, the scope of which is to be determined by the appended claim.

I claim as my invention:

The combination in a gas-heated pressing

machine having a stationary pressing element and a bodily movable pressing element, a pair of burners, one disposed in the stationary element and the other disposed in the movable element, a main conduit leading from a source of gas supply, a valve in the conduit, branch conduits leading from the main supply conduit to each of the respective burners, the conduit leading to the movable member being flexible, and a heat sensitive means associated with one of said elements and connected with the valve for controlling the operation of the same to simultaneously and equally regulate the supply of gas to both of said burners.

ANTON ZEMAN.
